UNITED STATES PATENT OFFICE.

WILLARD McC. REID, OF PORT CLINTON, OHIO, ASSIGNOR TO REID-GEISLER MANUFACTURING COMPANY, OF CHICAGO, ILLINOIS, A CORPORATION OF ILLINOIS.

HUMIDIFIER.

1,243,975.

Specification of Letters Patent. Patented Oct. 23, 1917.

Application filed November 17, 1916. Serial No. 131,906.

To all whom it may concern:

Be it known that I, WILLARD McC. REID, a citizen of the United States, and a resident of Port Clinton, in the county of Ottawa and State of Ohio, have invented a certain new and useful Humidifier; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to means for humidifying the surrounding air or atmosphere. It particularly has for its object to humidify the air in a room which is heated by artificial heating means such as by a hot air furnace or a steam or hot water radiator. In order to show the practicability of my invention I have selected a form of construction in which it is embodied to show how such a structure may be made and the manner in which it may be used, it being understood, however, that different forms of structures may be made which contain the invention. The particular form selected is illustrated in the accompanying drawings.

Figure 1 of the drawing illustrates a perspective view of the device having the wick used in connection therewith removed and one of the walls broken away for purposes of better illustration. Fig. 2 illustrates a sectional view of the humidifier illustrated in Fig. 1, and Fig. 3 illustrates in a conventional way, a wick that may be used in connection with the device illustrated in Figs.

1 and 2.

1, Fig. 1, is a three part container. Aside from the outside walls with which it is provided it also has the inner walls 2 and 3, which divide the container into three parts. 45 Water may be contained in the two outer parts 4 and 5, and these parts may be connected together by means of a pipe 6 which form a connection between the two compartments 4 and 5, so that water placed in the 50 compartment 4 will flow to the compartment 5 and thus both compartments may be filled and the water will rise and be kept at the same level in the two compartments. The inner chamber 10 is provided with a V-

shaped wall 11 which extends from the upper edge of compartment 4 to the upper edge of the compartment 5, the corner of the V being located near the pipe 6 or the lower edge of the end walls of the container 1. The V-shaped wall 11 is provided with a plurality of holes 12 which permit the heated air to pass readily up through the V-shaped wall 11 when the container 1 is placed over a radiator or a hot air register. A wick 15 is laid upon the venticulated wall or member 11, and its ends extend over into and preferably to near the bottom of the compartments 4 and 5. The wick 15 is formed of open work to permit heated air to pass up through the humidifier. The wick being placed upon the perforated wall 11 not only acts by capillarity to draw the water from the compartments 4 and 5, but also acts siphonically to uniformly spread the water over the V-shaped member. The heated air thus rising from the register or from the radiator 20, will be charged with the water, which will be evaporated from all parts of the wick. Also, the V-shaped chamber extending to the top edges of the inner walls 2 and 3, will cause a somewhat larger quantity of the heated air to pass to the corners formed between the V-shaped walls and the walls 2 and 3, the V-shaped member operating somewhat to deflect the air current to the corners. This brings the greater quantity of the heated air to the points where the water first issues from the compartments 4 and 5 by the operation of the wick, so that the arrangement of the V-shaped wall and the wick is such that the wick will operate by capillarity and siphonically, and yet the heated air will be uniformly humidified.

I claim:

In a humidifier, a venticulated V-shaped member, communicating compartments located on the opposite sides of the V-shaped member, the corner of the V-shaped member being adjacent the plane of the bottoms of the compartments and the edges of the V-shaped member connected to the upper edges of the compartments, a wick located on the surface of the venticulated V-shaped member and extending into the compartments.

In testimony whereof, I have hereunto signed my name to this specification.

WILLARD McC. REID.
